UNITED STATES PATENT OFFICE.

JOHN C. BEARD, OF NEWTONVILLE, INDIANA.

LIFTING-JACK.

SPECIFICATION forming part of Letters Patent No. 250,188, dated November 29, 1881.

Application filed August 29, 1881. (Model.)

To all whom it may concern:

Be it known that I, JOHN C. BEARD, of Newtonville, Spencer county, Indiana, have invented a new and Improved Lifting-Jack, of which 5 the following is a specification.

The object of my invention is to provide a lifting-jack for wagons, of improved and simplified construction.

My invention consists of a bifurcated upright 10 frame carrying a vertically-sliding bar, which bar is provided at its upper end with a stepped head-block, the bar and head-block being adapted to be raised and supported in its elevated position for holding the load by a hand- 15 lever pivoted at its end to the vertically-moving bar, in connection with a swinging connecting-bar pivoted to the frame and to the lever.

In the accompanying drawings, Figure 1 is a front elevation, showing the parts in position 20 for supporting the load. Fig. 2 is a similar view, showing the parts in position ready for lifting the load; and Fig. 3 is a cross-sectional elevation on the line xx' , Fig. 1.

Similar letters of reference indicate corresponding parts.

In the drawings, A represents the bifurcated upright frame, and B represents the sliding bar, which is moved vertically between the parts $a a'$ of the upright by the hand-lever C, 25 which is pivoted at c to the sliding bar B. The lever C is formed with the offset or shoulder d near its upper end, and against this offset the rounded upper end of the swing connecting-bar D is held by the pivot e , which passes 30 through the upper end of this connecting-bar, and through the perforated plates $e' e'$, secured in proper position upon the sides of the lever C, as shown. The lower end of the connecting-bar D is pivoted at f to the bifurcated frame. 35 The upper end of the sliding bar B is formed with or provided with the head-block E, which is formed into the series of steps g for adapting the jack to be used for the forward and rear axle-trees of the wagon, and for wagons 40 of different heights.

To the upper ends of the parts $a a'$ of the bifurcated frame, upon both sides of the frame, are secured the plates $h h$, between which the vertically-sliding bar moves, and the lower end of the said sliding bar is provided with the 50 cross-plates $h' h'$, which form a cross-head to support and guide the lower end of the sliding bar in its vertical movement between the parts $a a'$ of the upright frame.

In use the lever C is first to be brought to 55 the position shown in Fig. 2, in which position the vertically-moving bar and head-block are at their lowest point in the frame, in which position the jack is ready to be placed under the axle-tree. When placed under the axle- 60 tree the lever C has only to be pressed down to the position shown in Fig. 1, which causes the load to be lifted and held until the lever is swung out again.

A series of holes, i , may be made in the frame 65 for adjusting the connecting-bar for causing the sliding bar to move vertically a greater or less distance, as desired.

Having thus described my invention, I claim as new and desire to secure by Letters Patent— 70

1. In a lifting-jack, the combination, with the bifurcated upright A and the moving bar B, of the lever C, provided with the shoulder d and the swinging connecting-bar D, substantially as and for the purpose set forth.

2. In a lifting-jack, the combination, with the bifurcated upright A, provided with the plates h , and the moving bar B, provided with the stepped head-block E and the plates h' , of the lever C, provided with the shoulder d and 75 the plates e' , and the swinging connecting-bar D, substantially as and for the purpose set forth.

JOHN CRAVENS BEARD.
